MACHINE FOR MENDING RUNS IN KNITTED FABRICS

Application filed September 15, 1930. Serial No. 482,119.

The machine of the present invention is designed primarily for the purpose of mending runs in hosiery, or similar knitted fabrics which result from a progressive unlooping 5 of a line of interlooped cross-threads which gives to the run a ladderlike formation. In order to repair such run, it is necessary to progressively engage the cross-threads of the run and loop each of them over the next succeeding cross-thread of the ladder and to progressively feed forward the fabric at a speed commensurate with the re-looping operation.

To perform this operation successfully, it 15 is necessary that the looping needle during each cycle of operation engage but a single cross-thread on a lift of the needle and release the same from the hook on the down thrust of the needle, so that as the next succeeding loop is being formed the preceding loop will slip free from the needle and continue this operation with rapidity and precision until the entire run has been repaired.

It has heretofore been customary, in certain machines with which I am familiar, to 25 progressively space the cross-threads in preparation for the re-looping operation, so that the threads will be uniformly distended at equal distances from one another, but this 30 operation requires the exercise of extreme care in properly distending the fabric and in uniformly spacing the cross-threads before the looping operation begins, and also requires care in maintaining the space arrangement of a large number of cross-threads during 35 the entire progress of the work.

The present machine is designed to dispense with the necessity for thus initially 40 spreading and spacing the cross-threads by providing means which will progressively release each cross-thread of the series composing the run, concurrently with the lift of the hooked needle, so as to insure the engagement 45 on each needle operation of but a single cross-thread, which obviates the necessity for the exercise of extreme care in maintaining the spaced relationship above referred to, and enables the work to be performed by unskilled 50 operators with less opportunity for displace-

ment of the threads and resulting entanglement than has heretofore been the case.

The machine of the present invention is of extremely simple construction and is so constructed that it may be adjusted to secure 55 proper co-ordination between the operation of the needle and the operation of the releasing device which delivers the cross-threads to the needle in timed relation thereto.

In the drawings,

Fig. 1 is a front elevation of the machine; 60
Fig. 2 is a plan view of the shoe and associated releasing device taken on line 2-2 of Fig. 3;

Fig. 3 is a longitudinal sectional elevation 65 of the machine;

Fig. 4 is a sectional elevation of the driving mechanism taken on line 4-4 of Fig. 3;

Fig. 5 is a sectional elevation taken on line 5-5 of Fig. 3;

Fig. 6 is a view of the needle shaft and associated parts taken on line 6-6 of Fig. 1; 70
and

Fig. 7 is a plan view of the shoe and associated devices.

The machine, as a whole, is mounted upon 75 a table 10 and comprises a main frame including a lower arm 11, an upper arm 12, and a rear standard 13. The interior of the frame is cored to afford a housing for the working parts, and the upper arm terminates 80 at its forward or free end in a head 14 which is closed in front by a rectangular plate 15.

The lower arm has secured thereto a forward extending shoe 16, the upper surface 17 of which is rounded down at its outer end to afford a support over which the stocking or other knitted article is distended and supported. The upper wall of the shoe, at a 85 point immediately below the head 14, is provided with a slot 18, as best shown in Fig. 7. Immediately adjacent the forward edge of the slot, the shoe is provided with an inward extending lug 19, through which 90 is adjusted the threaded stem 20 of a releasing member which terminates at its upper end in an enlarged head 21, of flaring or conical formation, as shown, which extends 95 upwardly through the slot 18 and slightly 100

above the upper level of the surface of the shoe and thus constitutes a hump or protuberance.

The stem or the releasing member is obliquely disposed and threaded through the lug 19, so that the releasing member may be adjusted to cause a greater or less protrusion of the conical head end above the plane of the shoe, and the formation of the head is such that it affords an easy sloping, forwardly presented surface at an abruptly disposed end surface, with the result that as the fabric is fed forwardly the cross-threads will progressively ride up upon the easy forward surface of the head 21 and be released downwardly over the abrupt end surface and be engaged by the hook of the needle in a manner presently to be described.

The upper surface of the shoe coacts with a presser foot 22 which is in the form of a plate having an upturned toe 23 located in advance of the releaser head 21, and, as best shown in Fig. 2, the level of the foot, behind the upturned toe, is cut away to afford a T-shaped slot 24 which overlies and in part registers with the slot 18 in the shoe.

The relation of these parts is such that the releaser head 21 extends upwardly into the center of the slot 24, while the lower surface of the presser foot bears downwardly upon the surface of the shoe, so that the fabric on both sides of the run will be clamped and held in position to permit the cross-threads to successively ride up upon the forward or easy surface of the releaser head, thereafter to be carried downwardly, one at a time, in position to be caught by the needle.

The presser foot terminates at its rear end in a flange 25 which is secured by screws to the forwardly extending arms 26 of a yoke frame of angular formation, the rear arm 27 of which is adapted to be thrust forwardly to exert a downward pressure on the presser foot. The yoke frame is mounted on a pivot 28 carried by a bracket arm 29 which depends from the head 14 of the upper arm 12.

The arms 26 carry a cross-pin 30, on which is journaled a presser roll 31 which coacts with a pair of spaced serrated feed rolls 32 which are affixed and mounted upon a shaft 33 upon which is also mounted a spur gear 34 located between the serrated feed rolls 32. The serrated feed rolls, in conjunction with a presser roll 31, serve to feed the material forwardly in timed relation to the action of the hooked needle in such way as to successively present the cross-threads of the run to the needle, which will now be described.

The needle 35 is of the latch type commonly employed in machines of this character, and is provided with a hook at its lower end and protected by a latch which, as the needle descends, is forced open by the previously engaged cross-thread, leaving the hook exposed to engage the next cross-thread of the

run upon the succeeding lift of the needle in a manner well understood in the art to which the present invention relates.

The hooked needle is clamped within a head 36 at the lower end of a reciprocating stem 37 which is adjustably mounted within a tubular stem 38 slidably mounted within upper and lower bearings 39 and 40 in the walls of the head 14. A spring 41 encircles the stem 37, being interposed between the head 36 and the end of the tubular stem 38, which spring tends to force the inner stem 37 downward. The upper end of the inner stem is provided with a slot 42 within which is pivoted an adjusting cam lever 43 mounted upon a pivot 44 and provided with notches 45 and 46 located at varying distances from the pivot 44.

Each of the notches is adapted to engage with an edge of the tubular stem 38 at a point in approximate relation to the cam lever, the arrangement being such that as the cam lever is swung downwardly from a position indicated in Fig. 3, bringing the upper notch 46 into latching engagement, it will tend to lift the inner stem against the tension of the spring 41, thereby lifting the needle out of operative position.

A reciprocating movement is imparted to the needle through the action of an arm 47, the upper end of which is pivoted upon a pin 48 outwardly extending from a collar 49 slidably mounted upon the tubular stem 38 and held in adjusted position by means of a set screw 50. The arm 47 terminates at its lower end in a collar 51 which encircles a stud 52 eccentrically mounted upon and outstanding from the enlarged end 53 of a shaft 54 which is journaled through forward and rear journal mountings 55 and 56 formed across the interior of the upper arm. The rear end of the shaft 54 receives a beveled pinion 57 which meshes with a beveled pinion 58 on the upper end of a vertical transmission shaft 59, carrying a beveled pinion 60, which in turn meshes with a beveled pinion 61 upon a driving shaft 62, which carries a grooved pulley 63 combined with a hand-wheel 64.

The shaft 62 also mounts a disc 65 combined with a smaller disc 66 which is recessed or mutilated at 67 to coact with a star wheel 68 having radially extending slots 69 adapted to coact with the pin 70 on the disc 65 and constituting the well known Geneva movement.

The star wheel 68 is mounted upon a shaft 71 which also carries a spur pinion 72 meshing with a spur pinion 73 on an obliquely disposed shaft 74 which is mounted within journal mountings 75 and 76 in the lower arm 11, and the shaft, at its forward end, terminates in a worm 77 which meshes with a worm wheel 78, the teeth of which mesh with the teeth of the gear 34, which arrange-

ment provides for the transmission of a step-by-step rotary feeding movement to the serrated feed rolls 32.

The arm 27 of the presser yoke is acted upon by a spring 78 which encircles a rod 79 provided with adjusting nuts 80 for adjusting the tension of the spring. The rear end of the rod is pivoted upon a pin 81 carried by a lug 82 depending from the upper arm 12. The free end of the presser yoke and presser foot and presser roll carried thereby, may be lifted by the action of the cable 83 which connects with a finger 84 outwardly extending from the arm 27, which cable passes over a pulley 85 and extends downwardly to a treadle (not shown), or other convenient operating mechanism.

In order to protect the fabric from becoming entangled within the gearing, a guard plate 86 is positioned to overlie the worm gear 78, being notched in its forward edge 87 to embrace the serrated feed rolls 32, as shown in Fig. 7.

Operation

In operating a machine of the present invention, the stocking or other knitted article to be repaired is spread evenly over the upper surface of the shoe in position to bring the run into line with the releasing head 21, and the first cross-thread of the run is brought behind the releasing head in position to be engaged by the hook of the needle.

The initial adjustment of the machine may be effected by turning the hand-wheel 64, but after the needle is properly engaged with the first cross-thread the machine may be operated by power by the pulley 63. The attendant holds the fabric with the run continually in line with the releasing head, and the fabric on either side of the run is clamped and held by the presser foot, and as the machine is operated the serrated feed rolls 32 will draw the fabric inwardly in successive step-by-step operations which are properly timed to bring each succeeding cross-thread to the apex of the releasing head concurrently with the lift of the needle as it carries upwardly the previously engaged cross-thread. As the needle descends, the latch will be lifted by the previously hooked cross-thread, and on the next lift of the needle the cross-thread last released from the head 21 will be caught by the hook and carried through the loop formed by the preceding cross-thread, which latter then slides over the latch and is finally released.

The intermittent operation of the serrated feed rolls is so timed that material will be drawn forwardly concurrently with the lift of the needle, so that the release of each cross-thread from the releasing head will be occasioned by the conjunct pull of the material forwardly and the upward tension exerted by the needle in lifting the previously

engaged cross-thread, so that each newly released cross-thread will lie in position to be engaged as the needle descends, the periods of rest in the feeding operation occurring concurrently with the descending movements of the needle. The fabric will thus be held stationary after each releasing operation, so that the cross-thread just released will occupy exactly the proper position to be engaged by the hook of the needle on the next lifting operation, and in order to enable the releasing head to be exactly positioned to afford the necessary protrusion to provide for the stretch in the fabric and the operations of the needle, the releasing head is made adjustable in the manner indicated.

The arrangement is one which obviates all necessity for any preliminary stretching or spacing of the cross-threads along the run, since each cross-thread in succession is individually released at the proper moment to be engaged by the needle.

The attendant is thus enabled to center attention solely upon the necessity for feeding the run in proper alignment with the presser foot and the releasing device, and need pay no attention to the spacing of cross-threads in advance of a point where the looping operation is performed. The device, as a whole, is simple in construction and the working parts are so arranged that they may be accurately adjusted to secure the exact correlation required in successively feeding and releasing the threads to the needle.

Although the invention has been described with particularity, it is not the intention to limit the claims to the precise mechanism shown, since variations thereof may be introduced without departing from the spirit of the invention.

I claim:

1. In a machine for repairing runs in fabrics, the combination of a latched hooked needle and means for reciprocating the same; of a feeding surface for the fabric apertured to provide for the reciprocations of the needle, and a member extending above the plane of the feeding surface in proximity to the needle and adapted to permit the individual cross-threads of the run to successively slip over the protuberant member in position to be engaged by the needle.

2. In a machine for repairing runs in fabrics, the combination of a latched hooked needle and means for reciprocating the same; of a feeding surface for the fabric apertured to provide for the reciprocations of the needle, a member extending above the plane of the feeding surface in proximity to the needle and adapted to permit the individual cross-threads of the run to successively slip over the protuberant member in position to be engaged by the needle, and means for feeding the fabric and securing successive release

of the cross-threads at a speed commensurate with the reciprocations of the needle.

3. In a machine for repairing runs in fabrics, the combination of a latched hooked needle and means for reciprocating the same; of a feeding surface for the fabric apertured to provide for the reciprocations of the needle, a member extending above the plane of the feeding surface in proximity to the needle and adapted to permit the individual cross-threads of the run to successively slip over the protuberant member in position to be engaged by the needle, and means for intermittently feeding the fabric and securing successive release of the cross-threads at a speed commensurate with the reciprocations of the needle.

4. In a machine for repairing runs in fabrics, the combination of a latched hooked needle and means for reciprocating the same; of a feeding surface for the fabric apertured to provide for the reciprocations of the needle, a member extending above the plane of the feeding surface in proximity to the needle and adapted to permit the individual cross-threads of the run to successively slip over the protuberant member in position to be engaged by the needle, means for feeding the fabric and securing successive release of the cross-threads at a speed commensurate with the reciprocations of the needle, and a presser member adapted to compress the fabric onto the feeding surface in a region closely adjacent to the protuberant member.

5. In a machine for repairing runs in fabrics, the combination of a latched hooked needle and means for reciprocating the same; of a feeding surface for the fabric apertured to provide for the reciprocations of the needle, a member extending above the plane of the feeding surface in proximity to the needle and adapted to permit the individual cross-threads of the run to successively slip over the protuberant member in position to be engaged by the needle, means for intermittently feeding the fabric and securing successive release of the cross-threads at a speed commensurate with the reciprocations of the needle, and a presser member adapted to compress the fabric onto the feeding surface in a region closely adjacent to the protuberant member.

6. In a machine for repairing runs in fabrics, the combination of a latched hooked needle and means for reciprocating the same; of a feeding surface for the fabric apertured to provide for the reciprocations of the needle, a member extending above the plane of the feeding surface in proximity to the needle and adapted to permit the individual cross-threads of the run to successively slip over the protuberant member in position to be engaged by the needle, means for feeding the fabric and securing successive release of the cross-threads at a speed commensurate with

the reciprocations of the needle, and an adjustable presser member apertured to permit reciprocation of the needle and positioned to bring the protuberant member within said aperture and adapted to compress the fabric upon the feeding surface in a region closely adjacent to the protuberant member.

7. In a machine for repairing runs in fabrics, the combination of a latched hooked needle and means for reciprocating the same; of a feeding surface for the fabric apertured to provide for the reciprocation of the needle, a member extending above the plane of the feeding surface in proximity to the needle and adapted to permit the individual cross-threads of the run to successively slip over the protuberant member in position to be engaged by the needle, means for intermittently feeding the fabric and securing successive release of the cross-threads at a speed commensurate with the reciprocations of the needle, and an adjustable presser member apertured to permit reciprocation of the needle and positioned to bring the protuberant member within said aperture and adapted to compress the fabric upon the feeding surface in a region closely adjacent to the protuberant member.

8. In a machine for repairing runs in fabrics, the combination of a latched hooked needle and means for reciprocating the same; of a feeding surface for the fabric apertured to provide for the reciprocations of the needle, a member extending above the plane of the feeding surface in proximity to the needle and adapted to permit the individual cross-threads of the run to successively slip over the protuberant member in position to be engaged by the needle, means for feeding the fabric and securing successive release of the cross-threads at a speed commensurate with the reciprocations of the needle, an adjustable presser member apertured to permit reciprocation of the needle and positioned to bring the protuberant member within said aperture and adapted to compress the fabric upon the feeding surface in a region closely adjacent to the protuberant member, and spring means for holding the presser member in spring-pressed relation to the feeding surface.

9. In a machine for repairing runs in fabrics, the combination of a latched hooked needle and means for reciprocating the same; of a feeding surface for the fabric apertured to provide for the reciprocations of the needle, a member extending above the plane of the feeding surface in proximity to the needle and adapted to permit the individual cross-threads of the run to successively slip over the protuberant member in position to be engaged by the needle, means for intermittently feeding the fabric and securing successive release of the cross-threads at a speed commensurate with the reciprocations

- of the needle, an adjustable presser member apertured to permit reciprocation of the needle and positioned to bring the protuberant member within said aperture and adapted to compress the fabric upon the feeding surface in a region closely adjacent to the protuberant member, and spring means for holding the presser member in spring-pressed relation to the feeding surface.
- 5 10. In a machine for repairing runs in fabrics, the combination of a hooked latched needle and means for reciprocating the same, a feeding surface apertured to provide for the reciprocation of the needle below the plane of the feeding surface, a protuberant member extending through said aperture and above the plane of the feeding surface and positioned to permit the cross-threads of the run to successively ride up and over the protuberant member in position to be successively engaged by the hook of the needle, feed roller means located in proximity to the protuberant member, and means for actuating the feed roller means to feed the fabric 15 at a speed commensurate with the reciprocations of the needle to effect the successive delivery of the cross-threads to the needle.
11. In a machine for repairing runs in fabrics, the combination of a hooked latched needle and means for reciprocating the same, a feeding surface apertured to provide for the reciprocation of the needle below the plane of the feeding surface, a protuberant member extending through said aperture and above the plane of the feeding surface and positioned to permit the cross-threads of the run to successively ride up and over the protuberant member in position to be successively engaged by the hook of the needle, feed roller means located in proximity to the protuberant member, and means for actuating the feed roller means to feed the fabric 20 at a speed commensurate with the reciprocations of the needle to effect the successive delivery of the cross-threads to the needle.
- 25 12. In a machine for repairing runs in fabrics, the combination of a hooked latched needle and means for reciprocating the same, a feeding surface apertured to provide for the reciprocation of the needle below the plane of the feeding surface, a protuberant member extending through said aperture and above the plane of the feeding surface and positioned to permit the cross-threads of the run to successively ride up and over the protuberant member in position to be successively engaged by the hook of the needle, feed roller means located in proximity to the protuberant member, and means for actuating the feed roller means to feed the fabric 30 at a speed commensurate with the reciprocations of the needle to effect the successive delivery of the cross-threads to the needle.
- 35 13. In a machine for repairing runs in fabrics, the combination of a hooked latched needle and means for reciprocating the same, a feeding surface apertured to provide for the reciprocation of the needle below the plane of the feeding surface, a protuberant member extending through said aperture and above the plane of the feeding surface and positioned to permit the cross-threads of the run to successively ride up and over the protuberant member in position to be successively engaged by the hook of the needle, feed roller means located in proximity to the protuberant member, means for intermittently actuating the feed roller means to feed the fabric intermittently at a speed commensurate with the reciprocations of the needle to effect the successive delivery of the cross-threads to the needle, and a presser foot positioned to contact with the feeding surface and provided with an aperture adapted to afford clearance for the upward protrusion of the protuberant member above the plane of the feeding surface.
- 40 14. In a machine for repairing runs in fabrics, the combination of a hooked latched needle and means for reciprocating the same, a feeding surface apertured to provide for the reciprocation of the needle below the plane of the feeding surface, a protuberant member extending through said aperture and above the plane of the feeding surface and positioned to permit the cross-threads of the run to successively ride up and over the protuberant member in position to be successively engaged by the hook of the needle, feed roller means located in proximity to the protuberant member, means for actuating the feed roller means to feed the fabric at a speed commensurate with the reciprocations of the needle to effect the successive delivery of the cross-threads to the needle, a presser foot positioned to contact with the feeding surface and provided with an aperture adapted to afford clearance for the upward protrusion of the protuberant member above the plane of the feeding surface, and means acting upon the presser foot for yieldably holding the same into compressing relation to the feeding surface in a region adjacent to the protuberant member.
- 45 15. In a machine for repairing runs in fabrics, the combination of a hooked latched needle and means for reciprocating the same, a feeding surface apertured to provide for the reciprocation of the needle below the plane of the feeding surface, a protuberant member extending through said aperture and above the plane of the feeding surface and positioned to permit the cross-threads of the run to successively ride up and over the protuberant member in position to be successively engaged by the hook of the needle, feed roller means located in proximity to the protuberant member, means for actuating the feed roller means to feed the fabric at a speed commensurate with the reciprocations of the needle to effect the successive delivery of the cross-threads to the needle, and a presser foot positioned to contact with the feeding

the protuberant member in position to be successively engaged by the hook of the needle, feed roller means located in proximity to the protuberant member, means for intermittently actuating the feed roller means to feed the fabric intermittently at a speed commensurate with the reciprocations of the needle to effect the successive delivery of the cross-threads to the needle, a presser foot positioned to contact with the feeding surface and provided with an aperture adapted to afford clearance for the upward protrusion of the protuberant member above the plane of the feeding surface, and means acting upon the presser foot for yieldably holding the same into compressing relation to the feeding surface in a region adjacent to the protuberant member.

16. In a machine for repairing runs in fabrics, the combination of a feeding surface provided with an aperture, a protuberant member located within said aperture and adjustable to bring its acting end above the plane of the feeding surface to the desired degree, said protuberant member being positioned to permit the successive cross-threads of the run to ride up and over the protuberant member, a hooked latched needle and means for reciprocating the same through the aperture in the feeding surface and in close proximity to the protuberant member to successively engage the cross-threads released from the protuberant member, and means for feeding the fabric at a speed commensurate with the reciprocations of the needle.

17. In a machine for repairing runs in fabrics, the combination of a feeding surface provided with an aperture, a protuberant member located within said aperture and adjustable to bring its acting end above the plane of the feeding surface to the desired degree, said protuberant member being positioned to permit the successive cross-threads of the run to ride up and over the protuberant member, a hooked latched needle and means for reciprocating the same through the aperture in the feeding surface and in close proximity to the protuberant member, to successfully engage the cross-threads released from the protuberant member, roller means for intermittently feeding the fabric at a speed commensurate with the reciprocations of the needle, and a train of connections, including a Geneva movement, for imparting step-by-step feeding movements to the roller means.

18. In a machine for repairing runs in fabrics, the combination of a frame comprising an upper arm and a lower arm, the lower arm having thereon a feeding surface adapted to support the fabric and the upper arm being positioned in overhanging spaced relation to the lower arm, the feeding surface being provided with an aperture; a protu-

berant member mounted below the feeding surface and having a head end extending through said aperture and above the plane of the feeding surface, roller feeding means mounted below the plane of the feeding surface and presenting an exposed portion of the roller in coacting relation to the plane of said feeding surface, a hooked latched needle positioned to reciprocate through the aperture in the feeding surface and in proximity to the protuberant member and the roller, a stem for carrying the needle reciprocally mounted within the upper arm, and a train of transmission connections between the needle-carrying stem and a feed roller for imparting feeding movements to the roller at a speed commensurate with the reciprocating movements imparted to the needle.

19. In a machine for repairing runs in fabrics, the combination of a frame comprising an upper arm and a lower arm, the lower arm having thereon a feeding surface adapted to support the fabric and the upper arm being positioned in overhanging spaced relation to the lower arm, the feeding surface being provided with an aperture; a protuberant member mounted below the feeding surface and having a head end extending through said aperture and above the plane of the feeding surface, roller feeding means mounted below the plane of the feeding surface and presenting an exposed portion of the roller in coacting relation to the plane of said feeding surface, a hooked latched needle positioned to reciprocate through the aperture in the feeding surface and in proximity to the protuberant member and the roller, a stem for carrying the needle reciprocally mounted within the upper arm, and a train of connections located within a frame and including means for reciprocating the needle and a Geneva movement for imparting intermediate step-by-step feeding movements to the feed roller at a speed commensurate with the reciprocations of the needle.

20. In a machine for repairing runs in fabrics, the combination of a frame comprising an upper arm and a lower arm, the lower arm having thereon a feeding surface adapted to support the fabric and the upper arm being positioned in overhanging spaced relation to the lower arm, the feeding surface being provided with an aperture; a protuberant member mounted below the feeding surface and having a head end extending through said aperture and above the plane of the feeding surface, roller feeding means mounted below the plane of the feeding surface and presenting an exposed portion of the roller in coacting relation to the plane of said feeding surface, a hooked latched needle positioned to reciprocate through the aperture in the feeding surface and in proximity to the protuberant member and the roller, a stem for carrying the needle reciprocally

mounted within the upper arm, a train of connections located within the frame and including means for reciprocating the needle and a Geneva movement for imparting intermediate step-by-step feeding movements to the feed roller at a speed commensurate with the reciprocations of the needle, and a presser foot positioned to act in compressing relation to the feeding surface and apertured to afford a clearance for the upward protrusion of the protuberant member and to provide for the reciprocations of the needle.

21. The method of repairing runs in fabrics, which consists in distending the run by stretching the fabric to align the run with the reciprocating looping needle, drawing the fabric forward from a point beyond the needle to advance the cross threads of the run successively to the needle, and lifting each cross thread singly as it reaches a position immediately adjacent to the needle, to properly position it with respect to the needle, and thereafter suddenly releasing it into the path of the needle.

25. In witness that I claim the foregoing I have hereunto subscribed my name this 10th day of September, 1930.

RALPH M. MARKUS.
